Application October 24, 1945, Serial No. 624,156

2 Claims. (Cl. 120—19)

1

This invention relates to writing instruments, and more specifically to pencils of the type having progressively feeding leads.

An object of the invention is to provide a writing instrument of the character described wherein the lead feeding control mechanism automatically locks itself into variously adjusted positions and is of simplified and improved form. Other objects and advantages of the invention will appear in the specification hereinafter.

In the drawing:

Fig. 1 is a longitudinal section, on an enlarged scale, through a pencil of the invention; and

Fig. 2 is a top plan thereof.

The invention is illustrated in the drawing to comprise a lead pencil type writing instrument including a point portion 10 which is centrally bored to accommodate in slide-fitting relation therein the writing lead which is illustrated at 12. A tubular casing 14 which may be formed of any suitable material such as plastic or metal or the like, is fitted at one end upon the point element 10 to extend therefrom axially of the lead carrying bore portion 16 of the element 10.

The casing 14 is longitudinally slotted as indicated at 18 in a side wall portion thereof, and a lead feeding control rod 20 is slip-fitted at one of its ends into the bore 16 of the element 10 so as to back-up the lead 12 and also cause the lead 12 to be progressively projected from the point end of the element 10 in response to longitudinal displacement of the control rod 20 relative to the casing 14. At its other end the control rod 20 is laterally bent as indicated at 22 and thereupon extends through the slotted portion 18 of the casing 14 at a point remote from said element 10, and terminates in a bent boss portion 25 which is thereby disposed externally of the pencil casing 14. The casing 14 is externally serrated or otherwise formed with series of detents disposed alongside the slot 18, as indicated at 26; the detents 26 being so formed as to provide series of notches into which the boss portion 25 of the control rod 20 is adapted to rest as the control rod is adjusted to various positions longitudinally of the casing 14.

It is a particular feature of the invention that the bore 16 of the element 10 is of such dimension as to closely fit upon the control rod 20 and the length of the lateral portion is so much less than the radial distance from the axis of the pencil to the detents that the rod is always deflected against the wall of the bore whereby to support the latter in rigid relation at any and all feed control positions of the rod 20. The rod

20 is formed of spring steel or any other material having suitable elasticity characteristics so that the mounting of the inner end of the control rod relative to the element 10 will cause the boss portion 25 of the control rod to be elastically biased into a corresponding notch 26. Thus, at each longitudinally adjusted position of the control rod 20 the mounting thereof and the resiliency characteristics thereof cooperate to provide automatic locking of the control rod relative to the casing 14; and thus it will be understood that in order to feed the lead as required for writing purposes it is only necessary for the user to manually deflect the boss or handle portion 25 of the control rod farther outwardly against the resiliency of the body portion of the control rod so as to unlock the control rod from the casing 14, whereupon the rod may be displaced longitudinally to push the lead 12 to project the required distance from the writing point of the element 10. Upon release of the control handle 25 the resiliency of the rod 20 will cause the latter to return toward its normal "set" position, whereby the handle or boss portion 25 will be seated within a notch so that the control rod 20 is thereby locked against retrograde displacement relative to the casing 14 so that the writing lead 12 will be thereby backed-up by the control rod 20 so as to resist writing pressures against the lead. Thus, it will be appreciated that the essential operative elements of the writing instrument of the invention are provided in structurally simplified and functionally improved form, and that the structural elements 35 of the writing instrument of the invention are particularly adapted to be relatively inexpensively manufactured and assembled to provide finally an unusually rugged writing instrument which is fool-proof in operation.

40 As illustrated in Fig. 1, the casing 14 is preferably extended beyond the range of movement of the control handle 25 so as to provide within the casing a reservoir for spare writing leads. Such provision may be readily effected by simply 45 inserting a plug 30 into the casing 14 so as to provide a bottom for the spare lead reservoir, and an eraser may be slip-fitted into the outer end of the casing 14 as indicated at 22 so as to provide simultaneously a readily available eraser 50 and an outer end plug for the spare lead reservoir, so that a supply of spare leads as indicated at 34 may be conveniently carried therein.

It will be appreciated that the structural elements of the writing instrument of the invention may be formed of any desired materials and

that the control rod 20 will preferably be formed of some highly resilient material to provide the automatic adjustment locking feature described hereinabove. Also, the extreme end of the element 10 will preferably be longitudinally slotted as indicated at 36 and squeezed into such form as to frictionally engage the writing lead as it is pushed upon by the control rod 20 so as to resist unintended forward feeding of the writing lead. It will also be appreciated that although only one form of the invention has been illustrated and described in detail it will be apparent to those skilled in the art that the invention is not so limited but that various changes may be made therein without departing from the spirit of the invention or the scope of the appended claims.

I claim:

1. A pencil comprising a body having a bore to accommodate in sliding relation therein a pencil lead, a lead feed control rod slidably mounted at one of its ends within said body bore to press against said lead for lead feeding purposes, said control rod and said body bore being so relatively dimensioned as to permit longitudinal sliding of said rod relative to said body while being axially guided thereby, said rod being formed of resilient material and having its other end portion bent laterally and terminating in a head, said body having a detent disposed to engage said head whereby to latch said rod in a feed adjustment position relative to said body, said rod being adapted to be elastically deflected by pulling outwardly upon said head end to permit unlocking of said rod relative to said body for longitudinal adjustment thereof relative to said body for lead feeding purposes, the length of the laterally bent portion of said rod being such

that the rod is always deflected against the wall of said bore.

2. A progressive feed pencil comprising a tubular body having a writing point portion bored to accommodate in sliding relation therein a pencil lead, a lead feed control rod slidably mounted at one of its ends within the said bore, said control rod and said body bored portion being so relatively dimensioned as to permit longitudinal sliding of said rod relative to said body while the former is axially guided thereby, said body being longitudinally slotted in a side wall thereof, said rod being formed of resilient material and having its outer end portion bent laterally to extend through said body slot and terminating in a boss, said body having a series of detents disposed to engage said boss at various positions thereof corresponding to longitudinally sliding adjustments of said rod relative to said body, said rod and laterally bent portion thereof being so constructed and arranged as to cause said rod to be always deflected against the wall of said bore, whereby said boss automatically locks said rod in its various feed adjustment positions while the rod may be elastically deflected by pulling upon said boss to disengage the latter from said detents whereupon the control rod may be manually displaced longitudinally of the body for lead feeding purposes.
